AND WAGON

Robert O. Jackson, Highland Park, Mich.

Application September 27, 1946, Serial No. 133,613

Term of patent 7 years

(Cl. D34—15)

To all whom it may concern:

Be it known that I, Robert O. Jackson, a citizen of the United States, residing at Highland Park, in the county of Wayne and State of Michigan, have invented a new, original, and ornamental Design for a Combined Tricycle and Wagon, for which the following is a specification, reference being had to the accompanying drawing, forming a part thereof, in which:

Figure 1 is a perspective view of the combined tricycle and wagon showing my design; and

Figure 2 is a top plan view thereof.

I claim:

The ornamental design for a combined tricycle and wagon, substantially as shown.

ROBERT O. JACKSON.
